UNITED STATES PATENT OFFICE.

JAMES Z. TUCKER AND LOUIS W. MARKWORT, OF ST. LOUIS, MISSOURI.

SPARKING PLUG.

1,205,289.

Specification of Letters Patent. Patented Nov. 21, 1916.

Application filed May 18, 1914. Serial No. 839,197.

To all whom it may concern:

Be it known that we, JAMES Z. TUCKER and LOUIS W. MARKWORT, citizens of the United States of America, and residents of the city of St. Louis and State of Missouri, have invented certain new and useful Improvements in Sparking Plugs, of which the following is a specification.

The primary object of this invention is 10 to provide an improved double sparking plug.

Another object is to provide a sparking plug that can be adapted to make either single or double sparks.

15 A further object is to provide improved means in a spark plug whereby the sparking gaps between the electrodes cannot become disarranged on account of one electrode becoming concentrically moved from 20 another electrode.

A still further object is to construct a spark plug with a series of electrodes in which one of the electrodes is made circular in shape so proper sparking is insured 25 regardless of what the concentric location of the other electrodes might be to the circular shaped electrode.

Other and further objects will appear in the specification and be specifically pointed 30 out in the appended claim, reference being had to the accompanying drawings exemplifying the invention, and in which,

Figure 1 is a vertical section taken through a spark plug, said plug being secured to a portion of an engine cylinder. Fig. 2 is an inverted view of Fig. 1, showing the sparking end of the spark plug.

Referring by numerals to the accompanying drawings: 1 designates a portion of an engine cylinder, said cylinder having an inverted opening 2 in which is mounted a sparking plug 3. This spark plug comprises a cylinder engaging portion 4 having an exteriorly threaded portion 5 and an interiorly threaded portion 6. Formed in the portion 4 of the spark plug is a shoulder 7. Mounted in said portion 4 is an insulated core 8, said core having an enlarged portion 9 formed thereon. Formed on the lower end 50 of said enlarged portion is a shoulder 10, said shoulder adapted to rest on a packing washer 11 which is mounted on the shoulder 7 of the cylinder engaging portion 4.

Engaged in the interiorly threaded portion 6 of the portion 4 is a threaded bushing 12, said bushing adapted to have its lower

end engage the upper shoulder 13 which is formed on the enlarged portion 9 of the insulated core 8. Formed in the core 8 is a centrally arranged opening 14, said core, at 60 its lower end, terminating in a chamber 15. Mounted in said opening 14 is the main or first electrode 16. The lower end of said electrode 16 has a depending portion 17 secured thereto, the lower end of said depending portion 17 being bent at right angles forming a sparking point 18. Carried by the electrode 16 is a collar 19 which is adapted to engage against a shoulder 20 formed at the upper end of the chamber 15. Mounted on the upper end of the electrode 16, and on the upper end of the core 8, is a cap 21, said electrode being held in position by the thumb nut 22 engaging against said cap. 70

Secured to the lower end of the core 8 are a pair of depending points 23, the lower end of said points being secured to the circular shaped portion 24, said portion 24 encircling the depending portion 17 of the electrode 16. These points 23 and circular shaped portion 24 provide an intensifier or 80 second electrode.

Secured to the lower end of the cylinder engaging portion 4 is a ground or third electrode 25, said electrode having an extending portion 26. 85

In the operation of this improved spark plug, one end 27 of the ignition circuit wires is held in contact with the first electrode 16 by the thumb nut 22 while the other end 28 of said ignition circuit is grounded at 29. When the ignition circuit is closed, the current, taking the path of least resistance, will travel the first electrode 16 and jump and spark at the gap 30 to the second electrode, and then will jump and spark at the gap 31 to the third electrode, thereby giving two sparks. 90

In the mounting of spark plugs on internal combustion engines, it quite frequently happens that the points of the electrodes get separated to such an extent that inferior sparks are made, and sometimes, none at all. In this improved construction, one of the electrodes, comprising a circular shaped portion, will prevent the aforesaid ailment on account of its position in relation to the other electrodes on account of the concentric relation that the first and third electrodes have to the circular shaped portion of the second electrode. The extending portion 26 of the third electrode 25 100

105

110

being in the position shown, will serve as a protector to the other electrodes when the spark plug is removed from the engine cylinder.

- 5 If it is desired at any time to convert this improved form of double spark plug into a single spark plug, the sparking point 18 of the first electrode 16 can be bent, as shown in dotted lines Fig. 1, to a point adjacent
- 10 to the end of the extending portion 26 of the third electrode 25, thereby reducing the width of the gap between the sparking point 18 and extending portion 26. This will, of course, put the second electrode out of commission.

Located on the depending portion 17 of the electrode 16 is an enlarged portion 32, said enlarged portion being located adjacent the lower end of the chamber 15, and forming 20 an annular passageway 33 between the wall of said chamber and said enlarged portion 32. This form of construction of the chamber 15 will provide means for cleaning the sparking points of the electrodes

after each explosion of the engine, as when the gases in the chamber 15 are ignited, the force of the explosion will have to be discharged through the annular passageway 33, and the force of the exhaust from said chamber striking against the bring points 30 of the electrodes will keep said points clean from soot or carbon.

What we claim is:

A spark plug having three electrodes, one of said electrodes having an annulus formed thereon, said annulus adapted to encircle one of said other electrodes, said encircled electrode being turnably mounted, said third electrode being located on the outside of said annulus and adapted to extend over said annulus, said annulus forming means of electric communication between said other electrodes.
